UNITED STATES PATENT OFFICE.

JAMES R. CABLE, OF TOLEDO, OHIO, ASSIGNOR TO PETER PETERSEN, OF TOLEDO, OHIO.

SAFETY-VALVE FOR FLUID-PRESSURE MAINS.

1,139,952.

Specification of Letters Patent. Patented May 18, 1915.

Application filed December 27, 1913, Serial No. 808,959. Renewed April 5, 1915. Serial No. 19,346.

To all whom it may concern:

Be it known that I, JAMES R. CABLE, a citizen of the United States, and a resident of Toledo, in the county of Lucas and State of Ohio, have invented a certain new and useful Safety-Valve for Fluid-Pressure Mains; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to valves and has for its particular object to produce a valve which will automatically close when the gas pressure in the gas main reduces below a certain amount and which will also automatically close when the outlet is closed. It provides a safety device which will close off the burner connection to a stove or a furnace when the pressure in the main falls below a certain amount and also when the burner valve is closed so that when the gas is turned on in a heater, such as a furnace, for the night if the gas in the main should fall below a certain pressure, the automatic valve will operate to close the gas off, and also when the burner valve is closed, if it is accidentally opened the automatic valve will operate as a safety to prevent escape of gas.

The invention may be contained in a great variety of structures. I have selected one construction and shall describe it hereinafter to illustrate how such construction may be made and operated.

The construction described is shown in the drawings wherein—

Figure 1 illustrates a sectional view of an automatic valve when closed and Fig. 2 illustrates a sectional view of the valve showing the valve open.

1, Fig. 1, is the valve body, and 2 is the gas main.

3 is the outlet leading from the valve.

The valve body is provided with a frusto-conical chamber 10 which contains an inverted cup 11 having substantially the same conical inclination that the chamber 10 has so that when the cup 11 is positioned at the lower end of the chamber 10, it will tightly fit the chamber. The chamber 10 is capped by the cap 12 having a spherical surface which is adapted to hold the cup 11 central by the action of the gas rising in the cham-

ber 10 which strikes the spherical surface of the cap 12 and glances to the corners formed by the chamber 10 and the cap 12 and tends to increase the pressure of the gas in the corners which keeps the cup 11 located centrally. An inlet port 13 is inclined upwardly from the threaded socket 14 in which the pipe 2 is secured so that the gas entering from the pipe or main 2 is directed diagonally upward into the chamber 10. The port 13 terminates at the side of the cup when the cup is in its lowest position in the chamber 10. It is effectually cut off when the cup 11 is in its lowest position. An outlet 15 extends diagonally downward from the top of the chamber 10 and communicates with the socket 16 in which the outlet to the burner pipe 3 is connected.

A narrow passage-way 17 is provided which extends to a point near the bottom of the chamber 10 and near the lower edge of the cup 11 when the cup is in its lowest position. This affords at all times some communication between the pipes 2 and 3 when the pressure is low and until the cup 11 falls to its lowest position. A vent 18 is located in the upper end of the cup 11 which permits the gas to pass out through the cup and thus form a circulation of the gas within the cup 11 when the cup 11 is located in the upper or intermediate part of the chamber 10. It also operates to allow the gas to freely pass from below to above the cup so as to allow the cup to drop freely by reason of its own weight. It will cause it to seat squarely and quickly on the bottom of the chamber. It permits the cup to fall and strike with some little impact or click on the bottom of the chamber.

A pin 20 having a handle 21 is mounted in the lower end of the valve body 1 and is provided with a suitable packing ring and material 22. If desired, a ball 23 may be secured to the end of the pin 20 which sets into a socket to further close the opening about the pin. In order to open the valve the pin 20 is raised which pushes on the bottom of the cup 11 which raises the cup 11 and pushes it to the top of the chamber 10. As soon as the gas passes upward through the port 13 it immediately passes through the narrow passage-way 17 which under normal pressure immediately raises the cup 11 and pushes it upward by the movement of the gas in and about the cup and holds it to the top of the chamber 10.

In the use of the device, the burner valve 30 connected in the outlet pipe 3 is first opened and then the pin 20 is pushed upward so that the ball 23 presses against the bottom of the cup 11 and raises the cup 11 a short distance whereupon the gas will flow through the pipe 3 and the cock 30. If the pressure in the main falls to such a degree that the movement of the gas through 10 the automatic valve will allow the cup 11 to fall by reason of the weight of the cup 11, the gas will be automatically closed off. If the gas valve is closed, accidental opening of the burner valve 30 will not permit the gas 15 to escape through the automatic valve and burner.

The invention may be modified by those skilled in the art without departing from the spirit thereof.

Having thus described my invention, what I claim as new and desire to secure by Letters Patent, is,—

1. The combination of a casing having a frusto-conical chamber, a frusto-conical cup 25 movable in the chamber, the chamber having an inlet port closed by the wall of the cup when the cup is in its lower position and an outlet port located in the upper end of the chamber, and a channel extending 30 from above the cup to a point near the lower edge of the cup when the cup is in its lowermost position.

2. The combination of a casing having a frusto-conical chamber, an inverted frusto- 35 conical cup located in the chamber, the chamber having an inlet port closed by the wall of the cup when the cup is in its lowermost position, means for directing an incoming fluid upward, the chamber having an 40 outlet port located in its upper end, and a channel extending from the upper end of the chamber to the lower end of the chamber and to a point near the lower edge of the cup when the cup is in its lowermost position.

3. The combination of a casing having a frusto-conical chamber, an inverted frusto- 45 conical cup located in the said chamber, the

bottom of the cup having an opening, the chamber of the inlet port closed by the wall 50 of the cup when the cup is in its lowermost position, the chamber having an outlet port located at its upper end, the chamber having a channel extending from the outlet port to a point near the lower edge of the cup 55 when the cup is in its lowermost position.

4. In an automatic valve, the combination of a body having a frusto-conical chamber, a frusto-conical inverted cup located in the chamber, an inlet port inclined upward 60 and having its inner opening located below the bottom of the cup when the cup is in position to close the chamber, an outlet passage extending to a point near the lower edge of the cup when the cup is in closed 65 position, a mechanical means for raising the cup, the cup being held in an open position by the circulation of the fluid therethrough and the cup having a pointed bottom the upper end of the said chamber being provided with a spherical surface the cup being centered in its uppermost position by the movement of the gas in the said chamber.

5. In an automatic valve, the combination of a body having a frusto-conical chamber, 75 a frusto-conical inverted cup located in said chamber, an inlet port inclined upward and having its inner opening located below the bottom of the cup when the cup is in position to close the chamber, an outlet passage 80 extending to a point near the lower edge of the cup when the cup is in closed position, a mechanical means for raising the cup, the cup being held in an open position by the circulation of the fluid therethrough, said 85 valve having an outlet port extending diagonally downward from the upper end of the chamber.

In testimony whereof, I have hereunto signed my name to this specification in the 90 presence of two subscribing witnesses.

JAMES R. CABLE.
